United States Patent Office

Des. 198,907
Patented Aug. 18, 1964

198,907

CHAIR

Warren D. Petersen, Redondo Beach, Calif., assignor to Schlumberger Limited, Houston, Tex., a corporation of the Netherlands Antilles

Filed Mar. 31, 1964, Ser. No. 79,286

Term of patent 14 years

(Cl. D15—1)

FIG. 1 is a side perspective view of a chair showing my design; and

FIG. 2 is a rear perspective view thereof.

I claim:

The ornamental design for a chair, substantially as shown.
